Stitched to the outer surface of the sheet 31 is a reinforcing strip 36, to which a plurality of buttons 37 are secured. The shield 23 has a portion which overlies the sheet 27 and has an extension which extends around the edges of the element 24 (with the exception of the upper edge, and which carries button holes to engage the buttons 37).

The device may be provided with several of the shields 23 so that the device may be used with clean ones attached while soiled ones are being laundered.

To use the device 25 the operator inserts the hand into the pocket formed between the stitching 34 and 35 with the palm of the hand facing the assembly 26, 28 and the surface of the shield 23 is placed in contact with the skin of the person being massaged. Then the operator goes through the process of massaging in the usual way. Now due to the fact that the sheets 26 and 28 have the sleek or satiny faces in contact, the motion of the hand moves the sheet 28 without moving the sheet 26. Therefore the surface of the skin of the person being treated is not rubbed and irritated, and consequently all of the effort put into the massage is applied to the internal structure of the flesh.

I have found that the device is a great beauty aid in connection with the massaging of the face, the neck and other parts of the body to be beautified.

Although I have herein shown and described one embodiment of the invention and two modifications thereof, it will be understood that these embodiments are shown merely to teach others the practice of the invention, instead of being limitative.

It is obvious that many changes may be made in the arrangements herein shown and described within the scope of the following claims.

What is claimed is:

1. In a massaging device, a pair of sheets of satin

secured together about the perimeters thereof, the smoother surfaces of said sheets being in contact with one another and the warp of one of said sheets being disposed at a substantial angle with respect to the warp of the other of said sheets.

5 2. In a massaging device, a pair of sheets of satin secured together about the perimeters thereof, the smoother surfaces of said sheets being in contact with one another and the warp of one of said sheets being disposed at an angle of 90° with respect to the warp of the other of said sheets.

10 3. In a massaging device, a pair of sheets of satin secured together about the perimeters thereof, the smoother surfaces of said sheets being in contact with each other and the warp of one of said sheets being disposed at a substantial angle with respect to the warp of the other of said sheets, fabric means forming a pocket with the outer face of one of said sheets, and a fabric member covering the outer face of the other of said sheets and detachably secured to said first outer face.

15 4. In a massaging device a pair of sheets of satin secured together about the perimeters thereof, the smoother surfaces of said sheets being in contact with each other, and one of said sheets being formed of "nylon", the warp threads of one of said sheets forming an angle of 90° with respect to the warp threads of the other.
